UNITED STATES PATENT OFFICE.

GEORGE B. DOREY, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CAR-DOOR-OPERATING MECHANISM.

Application filed August 22, 1923. Serial No. 658,695.

This invention relates to improvements in car door operating mechanisms.

It is an object of my invention to provide a simplified construction for eliminating the usual torsional strain on a door operating shaft when the dump doors are in closed position, by directly supporting the door on the door operating shaft.

It is also an object of my invention to avoid the use of unnecessary moving parts between a door and shaft. As is well known to those skilled in the art, there are two general methods of supporting car doors in wide use, one of which employs a sliding latch or movable element attached to the door and adapted to rest on the shaft when the door is in closed position; the other depends upon the bodily movement of a shaft from a position adjacent the free edge of the door to a position under the same. Both of such methods being dependent for their locking action on moving parts are necessarily complicated, uncertain in action and excessive in weight, and it is the purpose of this invention to secure all the advantages of such operating mechanisms without the complications and disadvantages incidental thereto.

Another object of my invention is to provide a door adapted to be raised by a flexible element winding on a shaft and to relieve the flexible element of the weight of the door at a point intermediate the opened and closed position thereof.

Another object of my invention is to provide a rotatable shaft which will move a door to fully closed position and thereafter have rotary movement in the direction employed to close the door but independent of any further movement of the said door.

A still further object of my invention is to provide a flexible connection between an operating shaft and drop door which will directly support the same from the shaft when the door is open.

My invention further resides in the simple means on or constituting parts of the door to rigidify the same and eliminate warping and distortion thereof in order that the operating mechanism may at all times properly engage the doors and assure effective closure thereof.

This invention further consists in the novel combinations of the parts and devices

herein shown, described and made the subject matter of the claims.

In the drawings forming a part of this specification, Figure 1 is a plan view of a portion of a drop bottom gondola car showing my improvements in connection therewith, parts being broken away to more clearly illustrate some of the features. Figure 2 is a sectional elevational view of a portion of the car, taken on a line corresponding substantially to the line 2-2 of Figure 1. Figure 3 is a vertical sectional view taken substantially on line 3-3 of Figure 1 and illustrating the pawl and ratchet locking arrangement for locking the winding shaft against reverse rotation. Figure 4 is a transverse, sectional view taken on a line corresponding substantially to line 4-4 of Figure 1 and showing the door raising and locking mechanism when the door is fully closed and locked. Figure 5 is a transverse sectional view taken on a line corresponding substantially to line 5-5 of Figure 1 but showing the door in open position and depending from the winding shaft. Figure 6 is a detail sectional view similar to Figure 4 except that the door is shown in partially opened position and the door and associated parts of the mechanism are shown in a different relation, such as will hereinafter be fully explained. Figure 7 is a detail sectional view of the outer end of the door and associated parts of the mechanism taken on a line corresponding substantially to line 7-7 of Figure 1. In said illustration, the flexible connection extending between the door and shaft has been omitted in order to show more clearly the locking action between the shaft and the door when the latter is closed. Figure 8 is a detail sectional view similar to Figure 7, except that the door is shown in a partly opened position and illustrating the same and associated parts in a different relation, such as will hereinafter be fully explained.

Referring now to the drawings, wherein the mechanism is shown as applied to a drop bottom door car of well known form, having, generally, a plurality of doors on each side of the center sill, the number of which may be varied. I have illustrated only such doors as it is evident that the embodiment of the invention is the same whether employed with one or more doors. The car, as shown,

is provided with a center sill 10, crossbeams 11, side sill 12, side wall 13, and crossbeam covers 14. The floor adjacent the front edge of the door is indicated at 15 and the floor 5 adjacent the rear edge of the door at 16, while a metallic plate is provided, as at 17, for the purpose of sealing the opening between the rear edge of the dump door and floor 16. The door 18 is pivotally mounted 10 along its inner edge on hinge pivots 19 which are carried by hinge brackets 20 secured to the center sill 10. The said door 18 is reinforced by means of sections 21, preferably formed of angles, which extend lengthwise 15 of the door from the hinged end of the same to the free end thereof, being bent as at 22 to present a transversely widened space adjacent the free end of the door. A transversely disposed member 23 extends preferably in parallelism with the front edge of the door and also preferably is in the form of an angle. Both of said angles 21 and angle 23 have their horizontal flanges preferably directed inwardly and mitered as indicated at 24, said horizontal flanges being secured to the door boards 25 by means of bolts or rivets 26 and brackets 27 unite the vertical flange of each angle 21 with the vertical flange of angle 23. One of said 20 brackets is disposed at each corner of the door and provided with angularly disposed flanges indicated at 28 and 29 whereby connections are established with angles 21 and 23, respectively. Said angularly related 25 flanges 28 and 29 are connected by means of a base portion or wall which preferably extends beneath the angles 21 and 23 and serves to greatly rigidify the door framework and prevent distortion of the same. Beneath the said horizontal wall 30 are a 30 plurality of vertical webs 31 and 32 spaced apart a sufficient distance to accommodate the flexible element 33 which may be a chain or other suitable flexible connection. Said flexible connection is attached at one 35 end to the shaft 34 in the manner herein-after described, and the other end thereof is fitted with a threaded eyebolt 35 which passes through transverse walls 36—36 connecting the aforesaid walls 31 and 32 of the bracket 27, said walls 31 and 32 being further connected by means of a wall 37 which extends upwardly and preferably of arcuate form providing a bearing for the flexible connection 33. Adjacent the flange 31 of the bracket 27, there is formed an extension 38 which preferably extends outwardly beyond the side edge of the door and also beyond the free edge thereof, the under surface 39 being preferably flat and constituting a shoe extending at such an angle to the plane of the door as to be substantially tangent to an arc struck from the axis of the shaft 34, the said shoe being adapted to have co-operating engagement with a sup-

porting member 45 carried by the shaft. During the opening and closing operations of the door, the nose or extreme edge of the bracket 38 must clear the shaft and is slightly curved as indicated at 40 and slopes upwardly and away from the shaft as indicated at 41 in order to prevent fouling between the door and shaft. The bracket portion 38 is braced to the vertical flange 28 by means of a triangular, horizontally extending wing as indicated at 42.

The door supporting shaft 34 is located adjacent the free edge of the dump door, and out of the path thereof, passing through apertures which are formed in the ends of the crossbeams 11. Bearing castings 43 reinforce the crossbeams around the aforesaid apertures and each is provided with a bearing portion 44 within which the shaft is rotatably mounted. Door supporting members 45 are rigidly mounted on the shaft 34, being preferably disposed near each corner of the door. The door supporting members may be keyed to the winding shaft as indicated at 45^a, and also bolted to the shaft as indicated at 45^b, to prevent shifting of same longitudinally of the shaft. Each of said supporting members 45 is provided with a plurality of walls 46—46 spaced apart to receive the terminal link of one end of the flexible connection 33 which is thus secured to the shaft by a pin 47 passing through both walls 46—46 and the said terminal link. The portion of the supporting member 45 to which the flexible connection is secured, 100 is preferably disposed to one side of the door and the member is there formed with a winding sheave and provided with a guideway 48 adapted to guide the flexible element as it winds on the sheave and, inasmuch as 105 the preferred construction is to secure the flexible connection to the door at an appreciable distance inwardly from the side edge thereof, said flexible connection is adapted to wind on the shaft partly outwardly of the 110 plane defined by the adjacent side edge of the door and partly inwardly of such plane. The flexible element 33 is adapted to wind partly on the sheave portion of the member and partly on the periphery of the shaft, the 115 aforesaid guideway 48 extending spirally from a point adjacent a side edge of the door to a point in the plane of movement thereof, it being understood that the sheave portion of greatest diameter is preferably 120 disposed to one side of the door and the portion of reduced diameter in the plane of movement of the said door. As above indicated, the flexible element winds partly on the sheave and partly on the shaft, the 125 diameter of the sheave portion of the winding member decreasing until such time as it merges with the periphery of the shaft as indicated at 49. Intermediate the convolutions of the flexible element, the winding member 130

is provided with a door supporting seat, said seat in this case being a shoulder 50, preferably formed of arcuate shape and also preferably concentric with the axis of rotation of the shaft. Said shoulder 50, which is disposed in alignment with the inclined face 39 on the door is adapted to cooperate with the same to retain and lock the door in closed position and may preferably be formed integrally with the winding member 45 extending laterally therefrom and braced thereto by means of a plurality of ribs.

It will be noted that in this particular application of the improved mechanism, the guideway 48 does not extend beyond the point where the sheave merges with the shaft and in order to positively insure that the flexible element will be properly guided from one side of the shoulder 50 to the opposite side thereof, reliance is placed on the wall 31 which also operates to prevent the said flexible element from slipping sidewise from the ledge 37 when the doors are open.

Any suitable means for rotating the shaft may be provided but a preferred construction consists of pawl and lever mechanism of the type illustrated in U. S. Patent No. 1,284,056 granted to Argyle Campbell, November 5, 1918. The means employed to prevent reverse rotation of the shaft preferably consist of a locking ratchet wheel 51, non-rotatably mounted on the shaft and a locking pawl 53 for engagement with the said ratchet. The locking wheel 51 is preferably mounted on the shaft by making the adjacent portion thereof of square section as shown at 52 in Figure 3 and the aforesaid pawl 53 is pivotally mounted on a bracket 54 secured to the car framework. A locking cam 55, also pivotally mounted on the bracket 54, is adapted to be moved in the path of a portion of pawl 53 to lock the same in position.

Assuming the parts as shown in Figure 5 with the doors in opened position and supported directly from the shaft 34 by the flexible elements, free of the rail 56, the shaft 34 is rotated in a counter-clockwise direction as viewed in Figure 5. As this rotation occurs, it is evident that the flexible elements will wind on the sheave members, raising the door. During the initial rotation of the shaft, the shoulder 50 travels in the path of the door but above the same, it being understood that the length of the flexible element is so adjusted that the door does not raise sufficiently to be engaged by the said shoulder during the first revolution of the shaft. Continued rotation of the shaft further raises the door and on the second turn of the shaft the rounded corner 57 of the shoulder 50 engages the inclined face 39 on the door as shown in Figure 6 and operating to lift the door, as indicated in

Figure 6 by "b", is of a greater length than the effective lever arm from the axis of the shaft to the center of the flexible element as indicated by "a"; it is evident that the flexible element is now relieved of the load of the door, which is now carried by the shoulder 50. The relation between the respective co-operating engaging faces on the door lifting member and the door is shown in Figure 8 where the door closing operation is slightly more advanced than shown in Figure 6. The relative position of the parts with the door in locked position is indicated in Figure 7 wherein the flexible element has been omitted to more clearly show the locking action. With the shaft in such position, the door is positively secured in locked position for while the point of engagement between the door supporting member on the shaft and the door itself is located at a distance "c" from the axis of the shaft, the cooperating surfaces on the shaft and door respectively are so arranged as to counteract any turning tendency due to this lever arm. To this end, the surface 39 on the door is arranged to concentrate the load at a single point, through the line "d" which passes through the axis of the shaft. Said line "d" is the resultant of the combined vertical and horizontal forces as indicated by the lines "f" and "e" respectively. With this arrangement, it will be seen that the horizontally acting force as represented by the line "e" counteracts the turning movement on the shaft due to the aforementioned lever arm "c" and therefore the mechanism is self-locking.

As already pointed out, at a certain point in the door lifting operation, the flexible element is relieved of the weight of the door which has the effect of causing a differential travel between the door and the flexible element providing for a limited amount of slackness in the latter. Such slackness in the flexible element is taken up at the end of the door closing operation, making it possible to bring the door to a fully closed position and thereafter permits the giving of the shaft a further partial turn without any resultant lifting movement of the door; thus

a degree of free movement of the shaft, independent of movement of the door, assures positive locking at all points of a door or a series of doors and also renders it unnecessary to stop the shaft when the locking pawl 53 is midway between two teeth of the ratchet wheel 51, even though the door is closed but the shaft may be further rotated so that the pawl will be in full engagement with a tooth of the ratchet wheel.

While the arrangement shown herewith provides for an arcuate surface fixed to the shaft and a flat surface fixed to the door, it is evident that this arrangement might be

arcuate form. The arrangement of the operating mechanism and door bracing, as shown herewith, is applied in connection with a door of composite construction, but the same is equally applicable with a door of all metal construction. Nor do I wish to limit the application of this improved door operating mechanism to a gondola car with doors hinged longitudinally of the car as the same is equally applicable to cars having doors hinged transversely of the car, and wherever dump cars are used.

Although I have shown and described herein what I now consider the preferred manner of carrying out my invention, the same is merely by way of illustration and not by way of limitation. All changes and modifications are contemplated that come within the scope of the claims appended hereto.

I claim:

1. In a dump car, the combination with a door; of a sheave having a guideway provided with helical grooves of varying diameter, the largest of said grooves being disposed beyond the side of the door and the smallest of such grooves being disposed in the plane of movement of the door; and a flexible connection between the door and sheave adapted to wind in the said guideway.

2. In a dump car, the combination with a door; of a rotary shaft; a sheave secured to the shaft; a flexible element extending between the door and shaft, said element being adapted to wind on the sheave during the first stage of the door lifting movement and on the shaft during the last stage of the door lifting movement.

3. In a dump car, the combination with a door; of a rotary shaft; a sheave secured to the shaft; a flexible element adapted to wind partly on the sheave and partly on the shaft; and a door supporting seat rigidly secured to the shaft and disposed intermediate the turns of the flexible element on the sheave and shaft, respectively.

4. In a dump car, the combination with a door, of an operating shaft; a sheave fixed to the shaft; a flexible element adapted to wind partly on the sheave and partly on the periphery of the shaft; and a door supporting shoulder of arcuate form disposed intermediate the said turns of the flexible element and adapted to engage the door and retain the same in closed position.

5. In a dump car, the combination with a door; of an operating shaft; a sheave carried thereby; a flexible element connecting the sheave and door, said flexible element forming a direct support for the door when in open position, said flexible element being wholly disposed between the shaft and the door when the latter is in open position and adapted to wind on the shaft to raise the

door; and a door lifting arm carried by the shaft adapted to relieve the flexible connection by directly engaging the door and sustaining the weight thereof, the point of engagement between the door and a shaft being disposed above the level of the shaft.

6. In a railway car door raising and locking mechanism, the combination with a supporting framework; of a door, said door having a bracket fixedly secured thereto adjacent the free end thereof presenting a surface inclining downwardly relatively to the plane of the door and towards the pivotal axis of the said door; and a rotatably mounted member, held against bodily movement and adapted to have co-operating engagement with the aforesaid bracket to maintain the door in closed position, the co-operating surface on the said rotatably mounted member being of arcuate form.

7. In a railway car, the combination with a dump door; of a shaft disposed in a plane below the free edge of the door and out of the path thereof; a flexible element connecting the shaft and door, said flexible element being adapted to wind on the shaft to raise the door; a bracket carried by the door and projecting beyond the free edge thereof; and an arm carried by the shaft adapted to engage between the aforesaid bracket on the door and the shaft and relieve the flexible element of the weight of the door.

8. In a railway car, the combination with a dump door; of a shaft disposed adjacent the free edge of the door and out of the path thereof; an arm rigidly secured to the shaft and adapted to engage the under surface of the door to maintain the door in closed position; and a flexible element connecting the shaft and door, said flexible connection being secured to the shaft to one side of the arm and to the door to the opposite side thereof.

9. In a railway car the combination with a dump door; of a shaft disposed adjacent the free edge of the door and out of the path thereof; an arm rigidly secured to the shaft and adapted to engage the under surface of the same to maintain the door in closed position; a flexible element connecting the shaft and door, said element being adapted to wind on the shaft from one side of the arm to the opposite side thereof and passing in the plane of the arm on the opposite side of the shaft thereto; and a guideway on the shaft adapted to receive the said flexible element and guide the same from one side of the arm to the other.

10. In a railway car, the combination with a dump door; of a shaft disposed adjacent the free edge of the door; a sheave fixed to the shaft; a flexible element connected to the shaft and to the door and adapted to wind partly on the sheave and partly on the shaft, said flexible element being adapted to wind

in a guideway on the sheave and having the winding on the shaft separated from the sheave by means of a rib formed on the door and lying between the winding of the flexible element on the shaft and the sheave when the door is closed.

11. In a dump car, the combination with an underframe; of a drop door pivoted to the underframe, said door having re-inforcing members extending lengthwise of the door and a transversely disposed reinforcing member adjacent the free edge of the door; a bracket having flanges extending lengthwise of the door and transversely thereof and connected to the aforesaid respective reinforcing members; a rotatable shaft having a fixed pivotal axis adjacent the free edge of the door; and a flexible connection extending between the said shaft and the bracket on the door.

12. In a dump car the combination with an underframe; of a drop door having a reinforcing framework comprising spaced angles extending lengthwise of the door and an angle extending transversely thereof adjacent the free edge of the door and between the aforesaid angles, each of the aforesaid angles having a flange lying against the door and inwardly directed from the edge of the door; a bracket having longitudinally and transversely extending flanges secured to the said longitudinal and transverse angles; a rotatable shaft mounted in the underframe adjacent the free edge of the door; and a flexible connection secured to the shaft and to the aforesaid bracket.

13. In a railway car, the combination with a load sustaining door pivoted along one edge; of a reinforcement for the underside of said door comprising spaced sections extending lengthwise of the door and a transverse section extending substantially parallel with the free edge of the door; brackets at the junction of the longitudinal members and the transverse member, each of said brackets having angularly related flanges respectively secured to the aforesaid longitudinal transverse members, a connecting wall between the angularly related flanges and a section depending from the said connecting wall; a flexible element having one end secured to the aforesaid depending section; a rotatable shaft mounted in the underframe to

which the opposite end of the flexible connection is attached; and a seat on the shaft 55 over which a portion of the door is adapted to extend when in closed position.

14. In an operating mechanism for a door pivotally mounted on a suitable framework, the combination with a shaft mounted in 60 said framework to rotate about an axis parallel to and beyond the free edge of the door; of a flexible connection attached at one of its ends to said shaft and at its other end to the door and whereby elevation of the 65 latter is effected when the latter is rotated; a member affixed to the door at its free edge and provided with a load-bearing surface; and a load-supporting element rigid with 70 said shaft and having a bearing surface co-operable with said other bearing surface, the two said bearing surfaces engaging just prior to the door reaching its final closed position and at a distance from the axis of the shaft greater than the effective distance of the 75 flexible connection from said axis whereby, upon continued rotation of the shaft, the door is elevated at a proportionally faster rate than the take-up of the flexible connection and slack in the latter is permitted, said 80 bearing surfaces sustaining the load of the door when the latter is in closed position and the flexible connection thereby relieved of tension.

15. In a railway car, the combination with 85 a dump door pivoted to swing about a fixed axis; of a rotatable shaft, parallel to the pivotal axis of the door and disposed out of the path of the free edge of the door and located in a plane below that of the door when 90 the door is closed; seating means on and rigid with said shaft; co-operable seating means adjacent the free edge of the door and fixed with respect thereto; and a flexible connection between said shaft and door, said 95 seating means on the shaft being movable to a position intermediate the shaft and door and engageable with the fixed seating means of the door when the door is elevated to closed position by winding of said flexible 100 connection.

In witness that I claim the foregoing I have hereunto subscribed my name this 18th day of August, 1923.

GEORGE B. DOREY.
